UNITED STATES PATENT OFFICE.

W. THOMAS JORDAN, OF GRIFFIN, GEORGIA.

CAR-COUPING.

SPECIFICATION forming part of Letters Patent No. 307,957, dated November 11, 1884.

Application filed September 5, 1884. (No model.)

To all whom it may concern:

Be it known that I, W. THOMAS JORDAN, a citizen of the United States, residing at Griffin, in the county of Spalding and State of Georgia, have invented certain new and useful Improvements in Car-Couplings, of which the following is a specification, reference being had therein to the accompanying drawings.

My invention relates to certain improvements in car-couplings; and it is designed, objectively, to produce a device that shall be automatic in its operation. Further, it enables one to uncouple cars without going between them to lift the pin, and also provides a means whereby the cars may be made to remain uncoupled.

In describing the device reference is had to the drawings, in which Figure 1 represents an elevation of the device attached to a car, and Fig. 2 a vertical section of the same.

A designates a draw-head, being recessed internally on its upper side at B, the draft-pin hole being surrounded by a shoulder, C. The recess B extends on each side of the said shoulder. Pivoted in these extensions are the arms of a pendant, D, on the upper edge of which rests the pin E, preparatory to the act of coupling. The pendant has a curved face, so as to offer no resistance to the entering of the link. The lower internal part of the draw-head is recessed at F, to allow for the swing of the pendant. Extending across the body of the car is a shaft, G, turning in proper journals by means of the arms or handles H at each end thereof. Projecting from the shaft centrally is an arm, I, having its end flattened and curved downwardly and inwardly, as shown at K. A right-angle projection on each side terminates the said arm. The pin E is hung from the arm at about the point where it begins to curve downward and flatten, as shown at L. When the shaft is operated to carry the arm I upward, the chain M, carrying the said pin, follows the flattened portion, lifting the pin. The right-angle projections prevent the chain from falling to one side of the arm. A stop, N, on the car prevents a too great upward movement of the arm I, which would lift the pin from the hole in the draw-head. When it is desired that the pin should be kept elevated independently of the pendant, a lever, O, on one or

both sides of the car is moved, so that its head engages under one of the handles H, thus preventing its falling. A link (preferably one 55 that has one end weighted) when inserted in the draw-head forces the pendant backward and releases the pin, which falls into place. The raising of the pin and the withdrawal of the link allows the pendant to assume its normal position.

Having described the device, what I claim is—

1. A car-coupling consisting of a draw-bar containing a pendant, and a shaft journaled to 65 the car, and having projecting from it about centrally an arm with a flattened downwardly-curved continuation ending in right-angle extensions, said arm having a pin hung from it, the whole operated substantially as 70 and for the purpose specified.

2. A car-coupling consisting of a draw-bar having a recessed head, in which is pivoted a pendant, and a shaft journaled to the car, and having projecting from it about centrally an 75 arm with a flattened downwardly-curved continuation ending in right-angle continuations, and having hung from it a pin, the shaft having handles at each end, under which are adapted to fit one end of levers pivoted to the 80 car, substantially as and for the purpose specified.

3. A draw-bar having the upper internal part of its head recessed, and being provided with a shoulder around the pin-hole, and carrying a pendant provided with arms, by means of which it is pivoted to the said draw-head, said pendant having a rounded face and normally resting with its free end in a recess in the lower part of the said draw-head, substantially as and for the purpose specified.

4. In a car-coupling, a shaft journaled to the car and provided with handles at each end, said shaft having about central a projecting arm with a flattened downwardly-curved continuation ending in right-angle extensions, said shaft operating the draft-pin, as and for the purpose specified.

In testimony whereof I affix my signature in presence of two witnesses.

W. THOMAS JORDAN.
